UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed October 17, 1921. Serial No. 508,333.

My invention relates to drilling mechanism and more particularly to drilling mechanisms of the pneumatic feed type.

An object of my invention is to provide 5 an improved drilling mechanism. Another object of my invention is to provide an improved pneumatic feed type drilling mechanism of an exceedingly compact nature. A further object of my invention is to provide 10 an improved pneumatic drilling mechanism that may be very conveniently controlled. Other objects and advantages of my invention will hereinafter appear.

In the accompanying drawings I have 15 shown for purposes of illustration one form which my invention may assume in practice.

In these drawings,

Fig. 1 is a central vertical longitudinal section through the illustrative form of my 20 invention.

Fig. 2 is a transverse section on the line 2—2 of Fig. 1.

For purposes of description, the illustrative form of my invention may be divided 25 into the drilling mechanism, generally designated 1, and the feeding mechanism generally designated 2. The drilling mechanism comprises a cylinder 3 having a bore 4 in which a piston generally indicated by 5 is 30 reciprocable. The piston 5 has spaced heads 6 and 7 joined by a reduced portion 8 whereby an annular channel 9 is formed which serves in a well known manner in the distribution of motive fluid. A striking bar 10 35 is formed at the forward end of the piston 5 and by means of straight and spiral grooves 11 and 12, respectively, cooperating with a ratchet mechanism 13 and a chuck member 14, rotation is imparted to a drill 40 steel 15 at the same time that the percussive action of the piston is transmitted thereto by way of a striking plug 16. Fluid pressure to operate the piston is transmitted thereto by way of inlet ports 17, supplied 45 with fluid by passages 18 extending longitudinally in the wall of the cylinder, the supply of fluid to these passages being controlled by a manually controlled valve 19 in a well known manner. The exhaust from 50 the cylinder is accomplished by way of a pair of passages 20 traversing the wall of the cylinder at longitudinally separated points. Further description of the structure of this drilling mechanism and its mode 55 of operation is believed to be unnecessary as,

in its general detail, this motor is now well known and in general commercial use.

The cylinder member 3 has an integral extension 21, the cylinder bore 4 being closed off by a head member 22. The extension 21 60 at its rear end is closed by a piston head 23 which is slidable in a cylinder member 24, the latter being of such length that when the piston 23 is in the bottom of the cylinder, the entire motor cylinder lies within 65 the cylinder member 24. For the purpose of causing forward feed of the piston 23 and accordingly of the motor 1, I have arranged a longitudinally extending passage 25 in the wall of the cylinder member 3 and its ex- 70 tension 21 and fluid is supplied to this passage by way of a port 26 formed in the valve 19 in a well known manner, suitable means, not shown, being also provided to permit the exhaust of fluid from the lower end of the 75 cylinder through the port 25.

For the purpose of supplying cleansing fluid to the drill steel 15, I have arranged a long water supply tube 27 mounted in the piston 23 and extending completely through 80 the cylinder, piston, and striking bar and tappet of the motor. Fluid is supplied to this tube by way of a passage 28 formed in the piston 23 and a longitudinally extending passage 29 in the wall of the member 3 85 from a pipe 30 connected with a suitable source, the supply being controlled by a valve 31, the latter being connected for convenience to the handle 32 which enables the ready holding of the drill in desired position. It was noted that exhaust occurred by way of ports 20 to the space intermediate the cylinder 24 and the outside of the combined motor and piston member. A port 33 at the top of the frame permits a downwardly di- 90 rected exhaust.

From the foregoing description, the mode of operation of my improved drilling mechanism will be readily apparent. By manipulation of the valve 19 in a well known 100 manner, fluid pressure may be supplied through the passage 26 and passage 25 to the lower end of the feed cylinder, and the piston 23 together with the motor fed bodily forward. By suitable manipulation of the valve 19, fluid may also be admitted to the 105 passages 18 and cause reciprocation of the piston 5 and so percussion on and rotation of the drill steel 15. For the purpose of cleansing the hole of the cuttings, liquid 110

may be admitted by suitable adjustment of the valve 31 by way of ports 29 and 28 to the cleansing fluid supply tube 27 and so to the hollow drill steel. It will be evident that my improved mechanism permits the provision of a stoping drill having a feed capacity at least equal to that of any now on the market while economizing approximately one-third in the total length of the mechanism. This will permit working in much more cramped quarters than is now possible and accordingly the conducting of the operations in such close quarters in a much easier and quicker way than can now be done.

While I have in this application described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A drilling apparatus, fluid actuated feeding means including a feed cylinder, a hollow feed piston mechanism including a hollow piston rod therein, a drilling motor telescoping within said feed cylinder and carried by said piston rod spaced longitudinally from said hollow portion, and means for supplying motive fluid to said motor and said feed cylinder comprising passage means formed wholly in the walls of the hollow portion of said feed piston mechanism.

2. A drilling apparatus, fluid actuated feeding means including a feed cylinder, a hollow feed piston mechanism including a hollow piston rod therein, a drilling motor telescoping within said feed cylinder, and means for supplying motive fluid to said motor, and pressure fluid to said cylinder to feed the motor toward the work including passages formed wholly in the wall of said piston rod.

3. In a drilling apparatus, a feed cylinder, a drilling motor telescoping therein, a feed piston attached to said motor, and means for supplying cleansing fluid to a drill steel operated upon by said motor including a cleansing fluid supply tube extending completely through said motor and rigidly mounted in said feed piston.

4. In a drilling apparatus, a feed cylinder, a drilling motor telescoping therein, a feed piston attached to said motor, means for supplying cleansing fluid to a drill steel operated upon by said motor including a cleansing fluid supply tube extending completely through said motor and mounted in said feed piston, and means for supplying cleansing fluid to said tube including passages formed in said feed piston.

5. In a drilling apparatus, a feed cylinder, a drilling motor cylinder telescoping therein, means for supplying cleansing fluid to a steel operated on by said motor including a cleansing fluid supply tube extending through said motor, and means for supplying motive fluid to said motor, operating fluid to said feed cylinder, and cleansing fluid to said supply tube comprising passages formed in the cylinder of said motor, and controlling means therefor.

6. In a drilling apparatus, a feed cylinder, a piston rod mechanism including a hollow chamber, a drilling motor carried entirely within said piston rod mechanism, and means for supplying cleansing fluid to a drill steel operated on by said drilling motor including a tube extending completely through said chamber and said motor.

7. In a drilling apparatus, a fluid actuated feeding means including feed cylinder, a hollow piston rod therein having a piston secured thereto, a drilling motor carried within said rod, fluid pressure supply means, including passages formed in said rod for conducting fluid to said feed cylinder and said drilling motor, and means carried by said rod for controlling said supply means.

8. In a drilling apparatus, a fluid actuated feeding means including stationary feed cylinder, a hollow feed piston rod telescopically arranged therein and movable relative thereto, a fluid actuated drilling motor arranged in said rod and movable relative to said cylinder, and means including a valve carried by said movable rod for controlling the fluid flow to said motor and said feed cylinder.

9. In a drilling apparatus, fluid actuated feeding means including relatively movable telescopic cylinder and piston elements one of which is hollow, a fluid actuated motor arranged within one of said elements, and means carried by the movable element for controlling the fluid flow to said motor and said feeding means.

10. In a drilling apparatus, a feed cylinder, a hollow feed piston rod telescopically arranged therein, a drilling motor carried within said rod, cleansing fluid supply means for the drill steel including a tube extending completely through said piston rod and motor, and means formed in said rod for conducting liquid to said tube.

11. In a drilling apparatus, fluid actuated feeding means including a feed cylinder, a hollow feed piston rod telescopically arranged therein, a fluid actuated drilling motor arranged within said rod, and means formed in said rod for conducting motive fluid to said motor and operating fluid to said feed cylinder.

12. In a drilling apparatus, fluid actuated feeding means including a feed cylinder, a fluid actuated drilling motor telescoping

therein, a feed piston attached to said motor, and means for supplying motive fluid to said motor and operating fluid to said feed cylinder comprising passages formed in the cylinder of said motor, and controlling means for said fluid supply means.

13. In a drilling apparatus, fluid actuated feeding means including a feed cylinder, a fluid actuated drilling motor telescoping therein, a feed piston attached to said motor, cleansing fluid supply means for the drill steel extending through said motor, and means carried by said motor and movable therewith for controlling the fluid supply to said motor, said feeding means, and said cleansing fluid supply means.

14. In a drilling apparatus, fluid actuated feeding means including a feed cylinder, a fluid actuated drilling motor telescoping therein, a feed piston attached to said motor, and means for distributing motive fluid to said motor including exhaust passages communicable with the interior of said feed cylinder, and exhaust means formed in said feed cylinder.

15. In a drilling apparatus, fluid actuated feeding means including a feed cylinder, a hollow feed piston rod telescopically arranged therein, a fluid actuated motor to which said rod is attached, and means

formed in said rod for conducting motive fluid to and exhaust from said motor and operating fluid to said feed cylinder.

16. In a drilling apparatus, a feed cylinder, a hollow feed piston rod telescopically arranged therein, a drilling motor arranged within said rod, and means formed in said rod for conducting motive fluid to said motor and said feed cylinder and for conducting exhaust from said motor.

17. In a drilling apparatus, a feed cylinder, a drilling motor telescoping therein, a feed piston attached to said motor, and means for supplying cleansing fluid to a drill steel operated on by said motor including a cleansing fluid supply tube extending completely through said motor and mounted in said feed piston.

18. In a drilling apparatus, a feed cylinder, a drilling motor telescoping therein, a feed piston rod attached to the rear end of said motor and having a piston, and means for supplying cleansing fluid to a drill steel operated on by said motor including a cleansing fluid supply tube extending completely through said motor and said rod and mounted in said piston.

In testimony whereof I affix my signature.

ELMER G. GARTIN.
